(57) **CLAIM**

The ornamental design for a biological information measuring machine, as shown and described.

DESCRIPTION

FIG. 1 is a front, top, right perspective view of a biological information measuring machine showing my new design; FIG. 2 is a rear, top, left perspective view thereof; FIG. 3 is a front, top perspective view thereof; FIG. 4 is a front elevational view thereof; FIG. 5 is a left side elevational view thereof; FIG. 6 is a right side elevational view thereof; and, FIG. 7 is a top plan view thereof.

The dash-dot-dash lines depicting the boundaries of the claim and form no part of the claimed design, and the remaining broken lines illustrate portions of the biological information measuring machine that form no part of the claimed design.

1 Claim, 7 Drawing Sheets
